UNITED STATES PATENT OFFICE.

STEPHEN D. TUCKER, OF NEW YORK, N. Y.

SHEET-DELIVERY APPARATUS FOR PRINTING-MACHINES.

SPECIFICATION forming part of Letters Patent No. 293,121, dated February 5, 1884.

Application filed September 14, 1881. (No model.)

To all whom it may concern:

Be it known that I, STEPHEN D. TUCKER, a citizen of the United States, residing in the city of New York, county of New York, and 5 State of New York, have invented certain new and useful Improvements in Sheet-Delivery Apparatus for Printing-Machines, fully described and represented in the following specification and the accompanying drawings, forming 10 a part of the same.

This apparatus is designed to effect the delivery of sheets of varying sizes produced by the printing mechanism, its mechanisms being so constructed and organized as to be capable 15 of folding an eight-page or double sheet and four-page or single sheet and a two-page or half sheet of, say, an ordinary newspaper. It embraces a primary sheet-manipulating mechanism supplied with a folding-blade and means 20 for throwing it into and out of operation at certain revolutions of its carrier, and with supplemental devices whereby a gathering operation is effected, so that two sheets may be associated and folded together. This primary 25 mechanism is rotative in its operation, and has combined with it a secondary sheet-manipulating apparatus, the folding devices whereof are of the vibratory order, which secondary apparatus is organized with change-gearing, 30 so that while the primary apparatus always runs at one speed the secondary apparatus may be operated at three different speeds—viz., one that is uniform with that of the primary mechanism, one that is a lesser speed, 35 and a third that is a greater speed—so that the secondary apparatus may always be operated at the speed required to perform its work according to the requirements determined by the size and number of the sheets it is to 40 operate upon, which size is fixed by the manipulation of them performed in the primary apparatus.

A practical embodiment of the improvements embraced herein is illustrated in the drawings by such views as are necessary to 45 illustrate its construction and various adjustments.

In said drawings, Figure 1 illustrates a side elevation, Fig. 2 a plan view, and Fig. 3 an 50 end elevation, of the apparatus as adjusted and operating to fold and deliver single or four-page sheets. Figs. 4 and 5 are side elevations,

illustrating the adjustment of the apparatus and its operation in collecting two single or four-page sheets to make a double or eight-page sheet and the simultaneous folding of such collected sheets. Fig. 6 is a side elevation, and Fig. 7 an end elevation, of the apparatus as adjusted to fold and deliver two-page sheets, Figs. 8 and 9 being face and side elevations of the sheet-forwarding arms.

The structure of the apparatus will now be explained in detail, in order that its various operations may be readily comprehended.

The primary mechanism consists of rotating 65 cylinders or carriers A B, mounted in a suitable frame-work, geared together so as to run in unison by toothed wheels 101 102, and driven by a toothed wheel, 104, on the shaft 51 of the carrier B, which wheel, in practice, 70 will be connected by a train of wheels connecting with a driving-wheel on one of the shafts of a rotary printing-machine—such, for instance, as a toothed wheel on the shaft of one of the cutting-cylinders of such printing-machine—which cutting-cylinders, as is well understood, form a part of a rotating web-printing machine, whereby the printed web is severed or partially severed transversely upon suitable lines dividing such web into 75 sheets. As the collection and delivery of two single or four-page sheets, each of which is equal in length, or nearly so, to the circumference of the carriers A and B, is provided for in this apparatus, it is to be understood 80 that the type-cylinders will be twice the size of said carriers, so that when two single sheets are collected to form a single product said sheets shall bear different printed matter, and when single sheets are delivered singly two 85 duplicate forms are placed on the cylinder, and for two-page sheets four duplicate forms 90 are used.

The carriers A B will be slightly larger than the cutting-cylinders, but will run turn for 95 turn with them, so that the delivery apparatus here illustrated will run slightly faster than the printing mechanisms, the purpose being to cause the sheets severed or partially severed by the cutting mechanisms to be advanced rapidly enough to separate succeeding sheets a short distance apart, to provide a working-space between them, so as to permit their manipulation in the delivery apparatus without 100

one sheet interfering with another. The sheets are conducted from the cutting-cylinders to this delivery apparatus by means of the tapes 60 61, which are stretched, as is common, from 5 two rollers or sets of pulleys set just in advance of said cutting-cylinders, as is shown in the Patents Nos. 192,954, July 10, 1877, and 191,494, May 29, 1877, and others heretofore granted to me. The upper tapes, 60, run from the upper 10 rollers or pulleys into contact with the upper portion of the carrier A and return over pulleys 52 and 152, while the lower tapes, 61, run from the lower pulleys and return over pulleys 53. These tapes 60 61 form a conveyer 15 in connection with conductors 20, that bridge the space between the pulleys 53 and the carrier A, that direct the sheets in succession onto said carrier A. An auxiliary set of tapes, 62, are also provided, which run in contact with 20 the surface of the carrier A, pass over pulleys 54, and are stretched thence to compensating-pulleys 55, that are hung in drop-arms 56. These tapes are properly driven by means of pinions 70, 71, and 72 from the toothed wheel 25 101, and the tapes 62 are provided with vibrating rollers or pulleys 57, hung in arms from a shaft, 58, that is provided with a rock-arm, 59, and a connecting-rod, 68, that is adapted to be connected with a crank-arm, 69, 30 on the shaft 73, so that said tapes may be carried into contact with the carrier A, as is shown in Fig. 4, and they will be vibrated into and out of said contact, as is shown by said Figs. 4 and 5, for a purpose that will hereinafter appear.

The carrier A is provided with a set of grippers, 10, fixed on a rod that is journaled in said carrier, and provided with a rock-arm, 11, and an operative closing rod and spring, 40 12, in the usual manner common to such devices, their opening action being effected by contact of said rock-arm 11 with a stationary cam, 21, as is usual. Said carrier is also provided with a swinging folding-blade, 9, which is fixed upon a shaft, 8, journaled in the carrier-heads, one end of which shaft is provided with a two-branch rock-arm, 22, one of which branches is provided with a spring-seated rod, 23, and the other with a friction roller or stud, 50 24, that at times is engaged by a movable cam, 25. This cam 25 is carried by a rock-arm, 26, the vibrating movements of which are imparted by means of a rock-arm and a connecting-rod, 74, which may be adjusted so that its stud 55 or roller may travel in the path-cam 75, as in Fig. 4, or be disconnected therefrom, as in Fig. 1, in which latter case the stationary forward position of the cam 25 will be maintained by a thumb-screw, as 7, locking the arm of said cam 60 to the side frame, as in Figs. 1 and 2. When the blade 9 is moved forward and outwardly in passing the cam 25, as in Figs. 1 and 6, it has a true radial position, while when the said blade is relieved from the operation of said 65 cam, so that its spring-rod 12 may thrust its rock-arm outwardly, said blade is moved backward, so that its point is brought within the

periphery of its carrier A when the blade stands in the inclined position shown in Fig. 4.

The carrier B is provided with a fixed jaw 70 formed by one wall of an opening in its periphery and with a vibrating co-operating jaw, 5, substantially as is shown and described in Patent No. 143,674, October 14, 1873; but in this instance the vibrating jaw is constructed like the blade 9—that is, it is mounted upon a shaft, 27, that turns in the carrier-heads, which shaft has a two-branch rock-arm carrying at one end a spring-seated rod, 28, and at the other a stud or roller that travels 80 upon the cam 30, which cam is fixed to the frame-work and operates said jaw 5 at each revolution of the carrier B.

The secondary sheet-manipulating apparatus is driven by a longitudinal shaft, 110, 85 through a miter-wheel, 111, that is engaged by a similar wheel, 112, carried by a cross-shaft, 113, upon the opposite end of which shaft is a toothed wheel, 103, that meshes with the wheel 104 on the shaft 51 of the carrier B. 90 Motion is also derived from the shaft 113 to drive the cam 75 by means of a toothed wheel, 105, mounted upon the shaft 113, inside the frame-work, (see Fig. 2,) that meshes with a toothed wheel, 106, on the shaft 73. This 95 secondary sheet-manipulating apparatus is provided with vibrating folding and sheet-carrying mechanisms that operate to direct the sheets at right angles to their path of travel in entering the same. It embraces a 100 pair of sheet-carrying rollers, 65 66, that are provided with pinions 85 86, so as to run in unison, said rollers being rotated by means of a pinion, 87, carried by the roller 66, and a train of wheels, 88 89 90 91 92 95, which 105 derive motion from the counter-shaft 114, which derives its motion through change-gearing from the longitudinal shaft 110. This longitudinal shaft 110 is provided with three driving-wheels—viz., a sliding pinion, 98, and 110 two fast gear-wheels, 93 and 97. The wheel 96 is slid in and out of gear, as required, with a wheel, 93, of equal size, fast on the shaft 110, and the pinion 98 can be slid in and out of gear with a wheel of double its size, 115 100, fast on the shaft 115, which will make this latter shaft run at an equal speed and at half the speed of the shaft 110. The wheel 94 can be slid in and out of gear with the equal-size wheel 93, fast on the shaft 110, the pinion 116 can be slid in and out of gear with a wheel of double its size, 97, fast on the shaft 110, and the pinion 98 can be slid in and out of gear with the wheel of double its size, 99, fast on the shaft 114, so that this latter shaft can run at equal speed, at double speed, and at half the speed of the shaft 110. It will thus be apparent, that while the shaft 110 is constantly driven at the same speed given to the primary apparatus from the printing-machine, said shaft, primary apparatus, and printing-machine will run in unison, and that when the wheel 93 is geared with the equal-size wheels 94 96, and the wheel 97 is

disengaged from the pinion 116, and pinion 98 from wheels 99 100, as in Fig. 1, the secondary apparatus will be driven in unison or at the same speed as the primary apparatus and printing-machine, for the reason that the wheels 96, 93, and 94 are of equal diameter; also, that when the pinion 98 is geared with the wheels 99 100, and the wheels 94 96 are disengaged from the wheel 93, and the pinion 116 is disengaged from the wheel 97, the secondary apparatus, as in Figs. 4 and 5, will be driven at one-half the speed of the primary apparatus and printing-machine, for the reason that the driving-pinion 98 is of a diameter one-half that of the wheels 99 100; also, that when the pinion 116 is geared with the wheel 97, and the pinion 98 and wheel 94 are thrown out of action, as in Fig. 6, the secondary apparatus will be driven at twice the speed of the primary apparatus, for the reason that the driven pinion 116 is but half the size of its driving-wheel 97, which makes turn for turn with the carriers A B, and of course with the cutting-cylinders. The purpose and advantage of this change-gearing will be fully set forth in the description of the operation of the devices.

The secondary mechanism is provided at opposite sides with socket-arms 40 41, motion being communicated to the arm 40 by a rock shaft and arm, 42, and connecting-rod 43 from a crank-disk, 44, on the shaft 115, and to the rock-arm 41 by a rock shaft and arm, 45, connecting-rod 46, and crank-disk 47 on said shaft 115. The socket rock-arm 40 is always in operation, but may carry either a folding-blade, 31, the arms 32 of which are seated in socket-arms 40, as in Figs. 1 to 5, or a sheet-forwarder consisting of a roller, 33, and guide-plate 34, secured to said socket rock-arm 40 by arms 35, as in Fig. 7, which blade 31, thus vibrated, will enter between the rollers 65 66, or which sheet-forwarder, thus vibrated, will enter its guide-plate 34 between said rollers and bring its roller 33 into frictional contact with the roller 65. This socket rock-arm 41, not requiring to be constantly operated, has its rod 46 arranged to be disengaged from the crank-pin 4 and temporarily secured out of operation by a screw, 76, securing it to the side frame, as in Fig. 3, or to be adjusted into operative position, as in Fig. 7, where it is shown to be supplied with a sheet-forwarder consisting of arms 36, that carry a roller, 37, and guide-plate 38, the vibration of which sheet-forwarder will be made to alternate with those of the sheet-forwarder carried in the socket rock-arm 40, but not in equal times, for a reason that will hereinafter be apparent.

Depending from between the rollers 65 66, and in a vertical direction, is a cage made up of flat bars or wires 15 16, suspended to the frame-work, so as to form a receptacle into which the sheet emerging from between the rollers 65 66 may descend and rest in a vertical position in front of rollers 80 81, that have their axes parallel with those of the rollers 65

66, and which are driven by the wheels 89 90. With these rollers 80 81 a vibrating folding-blade, 17, coacts, which blade is carried by arms 82, projecting from a shaft that is vibrated by a rock-arm, 83, and a connecting-rod, 84, from a crank-pin, 3, that is secured upon the face of the wheel 95.

Sets of tapes 63 extend from the carrier B over a roller, 78, and outward in a plane just above the rollers 65 66, and return over pulleys 79 and under pulleys 50, with which tapes an under set, 64, co-operate, said tapes being stretched from the roller 78 and return over pulleys 77, and are driven by a pinion, 19, on the shaft of the roller 78, which gears with the wheel 102. These tapes, in connection with a lapping-guide, 150, form a conductor for conveying sheets from the primary apparatus to the secondary apparatus.

In connection with the carrier A is arranged a circular cutter, 48, the shaft of which is mounted in rock-arms 49, by which it may be depressed with its edge traveling in a groove 90 in the periphery of said carrier, as in Fig. 6, when it will operate to divide the sheets longitudinally, or it will let them pass uncut when raised out of such operative position, as in Fig. 1.

In order to a more ready understanding of the operations of these mechanisms, I will first describe the same in connection with the delivery of the single or four-page sheets—that is, sheets of a length equal to one-half the circumference of the type-cylinders and slightly shorter than the circumference of the carrier A, the circumference of which carrier is equal to the length of the sheet plus the working-space. When the mechanisms are arranged to operate upon such sheets, the tapes 62 will be thrown out of action by disconnecting the rod 68, and thus dropping the vibrating pulleys 57. The pinions 98 and 116 are then thrown out of engagement with the wheels 99, 100, and 97, as in Fig. 1, and the folding-blade 31 is adjusted in the socket rock-arms 40, while the socket rock-arms 41 are thrown out of action by disengaging the connecting-rod 46 from the crank-pin 4 and securing the same by the thumb-screw 76, as in Fig. 3. Thus adjusted, the mechanisms will all run in the same time. The cutter 48 will be adjusted in its raised position, and the cam 25 will be secured in its forward position by the thumb-screw 7, as in Fig. 1, so as to vibrate the folding-blade 9 at each revolution of the carrier A. Each single or four-page sheet conducted from the printing-machine by the tapes 60 61 will be guided onto the carrier A, its front or leading edge entered beneath the grippers 10 then open, which grippers will immediately close onto and seize said sheet, and the sheet will be carried onward around with said carrier. Its middle portion or line of ultimate folding will thus be led over the point occupied by the folding-blade 9, and as the stud or roller 24 of the folding-blade rock-arm 22 engages the cam 25 said blade will be thrust forward and outwardly, car-

rying the paper with it and entering the same between the stationary jaw and the vibrating jaw 5 of the carrier B, the grippers 10 being opened to release the forward end of the sheet at 5 the same time. As the carriers A B further revolve, the jaw 5 is quickly closed upon the bight or creased line of the paper by the action of the cam 30, thus clamping or securing the sheet to said carrier B, so that the sheet 10 shall thereafter be carried around by said bight or creased part. In such movement of it with the carrier B, the blade 9 being withdrawn as the cam 25 is passed, the sheet is drawn between the lapping-guide 150 and the periphery of the carrier B, its free ends being thus laid together, and is directed by the tapes 63 64 15 out over the rollers 65 66 until it is arrested by gages 120. Momentarily resting in these tapes, it is struck on a line at right angles with 20 its first fold by the downward movement of the folding-blade 31, which doubles or creases it into the nip of the rollers 65 66, which, revolving, cause it to descend into the cage or guide formed by the wires 15 16. In this cage 25 it rests in a vertical position before the folding-rollers 80 81, into the nip or bight of which it is doubled on a line parallel with its second fold by the movement of the blade 17, which is vibrated to perform that operation, said blade 30 being cut away at proper points of its edge to pass by the wires 15 16. The sheet thus a 35 third time folded, in passing between the rollers 80 81, emerges therefrom as in Fig. 3, and may be thence guided to any piling or further folding apparatus. If, now, it is desired to collect two such single or four-page sheets to make an eight-page or double sheet, so as to form a product consisting of two such sheets combined and folded together, the tapes 62 are adjusted so 40 as to be alternately rocked into contact with the lower surface of the carrier A, as in Fig. 4, and out of contact with such surface, as in Fig. 5, by connecting the rod 68 with the crank 69, as in said figure, whereupon during 45 a portion of one revolution of the carrier A the tapes 62 will be held in contact therewith, as in Fig. 4, and during the next revolution of said cylinder will be removed from such contact, as in Fig. 5. This converts the carrier A into a gathering-cylinder. The cam 25 is also relieved from its stationary position and made to vibrate at each second revolution of the carrier A by attaching the connecting-rod 74, that is connected to its rock-arm, to 55 the cam 75 by sliding the same on the shaft 73, so that the stud or roller 13 of the rod 74 will be engaged by said cam-groove, as in Figs. 4 and 5. This converts said carrier A into a combined gathering and folding cylinder, 60 as is explained in said Patent No. 191,494. With the mechanisms thus adjusted, the first sheet entering onto the carrier A will be seized by the grippers and carried around with said carrier into the control of the tapes 62, 65 at which time the cam 25 will be in its rearward position, and therefore will not operate the folding-blade. The forward end of this

sheet will be, when released by the grippers, sustained and carried onward by the tapes 62, which are then in their position of contact 70 with said carrier, said sheet thus making a revolution with said carrier A as a mere guiding-cylinder, without being affected by the folding-blade. As the forward edge of the sheet arrives at the upper side of said cylinder it receives upon it a second sheet coming from the printing mechanisms, the leading edges of the two sheets being seized by the grippers and carried around with the carrier A. In this revolution of said carrier the cam 25 75 is in its foremost position and the tapes 62 have dropped out of contact with the carrier, as in Fig. 5, in consequence of which the leading edges of the two sheets are released by the grippers, so as to be free just as the middle 80 or folding line of the two sheets is creased or doubled into the nip of the jaws of the carrier B, and thus doubled they are carried out over the rollers 65 66 of the secondary sheet-manipulating apparatus and rest against the 85 gages 12, precisely as has been described with reference to the single four-page sheets.

It will be observed that as two single or four-page sheets are brought one upon the other and folded so as to occupy the length 95 of but one or a single four-page folded sheet, there are just one-half the number of sets of such folded single or four-page sheets conveyed to the secondary sheet-manipulating apparatus, and consequently that if such apparatus be run at the same speed as the primary apparatus it will operate uselessly one-half of the time. To avoid this and yet perform the second folding of these once-folded pairs of sheets as rapidly as they can be gathered and folded, it is only necessary that the secondary apparatus shall run at one-half the speed it must have when manipulating single sheets. This is accomplished by throwing the wheels 94 96 out of gear with the wheel 93, and by adjusting the pinion 98 in gear with the wheels 100 99, as in Figs. 4 and 5. The motion of the primary apparatus will then be transmitted through the wheels 98 to the wheels 99 100, and thence to the devices 100 of the secondary apparatus, the speed of which, in consequence of the size of the pinion 98, will be one-half that of the primary apparatus, and as but half the number of sets of sheets 105 now require to be manipulated by said secondary apparatus, the movements of its said devices, the folding-rollers 65 66 80 81 included, will be properly timed so that each of their operative actions will be effective and sufficient to fold said once-folded sets of single or 110 four-page sheets a second and third times, as were the uncollected single or four-page sheets.

In producing half or two-page sheets, the tapes 62 are thrown out of action by disconnecting the rod 68. The cam 25 is secured in 115 its forward position by the set-screw 7. The cam 75 is disengaged from the rod 74, and the cutter 48 is lowered into operative relation to the carrier A, as in Fig. 6. Each single or 120

four-page sheet then conducted onto the carrier A will be severed longitudinally by the cutter 48, so as to produce two half or two-page sheets lying parallel or side by side, (proper printing-forms having been used,) which sheets will be conveyed by the tapes 63 64 into the secondary folding mechanism, where they rest against the gages 120 in a plane slightly above the rollers 65 66.

10 It will be observed that the longitudinal central meeting edges of these two half or two-page sheets occupy a central point immediately above the rollers 65 66, and consequently that no folding operation upon that line can be performed upon them by a folding-blade, as 31. In order, therefore, to further fold such half or two-page sheets, the said folding-blade 31 is removed, and the sheet-forwarders, composed of the rollers 33 37, with their guide-plates 34 38, are adjusted by their arms 35 36 in the socket rock-arms 40 41, as in Fig. 7, the latter socket rock-arm being now thrown into operation by adjusting the disconnected rod 46 upon the crank-pin 4.

25 It will now be observed that there are just as many sheets passing longitudinally into the secondary apparatus as in the first adjustment, where single or four-page sheets follow in succession to said apparatus, and that in consequence of the division of such sheets longitudinally into two-page sheets the number of sheets in said apparatus to be disposed of is doubled, and as this double number of sheets must pass between the rollers 65 66 in succession, so the 30 speed of such secondary apparatus must be increased twofold, and this is done by adjusting the pinion 116 into gear with the driving-wheel 97, the pinion 98 then being removed out of gear with the wheels 100 99, and the wheel 94 from gearing with the wheel 93, as is seen in Fig. 6. The motions of the secondary apparatus are thus made twice as often as that of the primary apparatus, for the reason that the driver 97, transmitting the motion of the latter, is twice as large as the driven pinion 116, and this, it will be observed, also doubles the speed of the folding-rollers 65 66 80 81. When a divided single or four-page sheet or two half or two-page sheets arrive in the secondary apparatus, one sheet-forwarding device will be quickly vibrated downward, its blade 34 deflecting the edge of the sheet underlying it, and the roller 33 pressing the same into contact with the roller 65, thereby causing the 45 edge of such sheet to enter between said rollers and be carried thereby down into the cage or guide 15 16, in front of the folding-rollers 80 81, through which it is quickly doubled by the folding-blade 17, and from which it emerges 50 a second time folded at right angles to its first fold. So soon as the rear edge of this sheet has passed the rollers 65 66, the second sheet-forwarding device is operated, its blade 38 and roller 37 operating in like manner to direct 55 and drive the second page sheet into the cage or guide 15 16. The two half or two-page sheets are thus quickly delivered out of the

tapes overlying the rollers 65 66, so as to make room for the next incoming pair of such sheets; but it will be observed that the last one will 70 remain a short time in the cage awaiting the second stroke of the folding-blade 17, but it will be folded through the rollers 80 81 in ample time to make room for the sheet from the rollers 65 66.

75 *Modifications.*—The primary sheet-manipulating apparatus might be constructed as is described in said Patent No. 191,494, which, like that here shown, is a rotating combined folding and gathering mechanism. Of course 80 the gathering and folding mechanism in the primary apparatus may be arranged so as to collect any number greater than two sheets, as may be desired, a corresponding arrangement of the change-gearing and secondary apparatus being made. The two collected single or four-page sheets may be pasted together, if desired.

85 The following broad subject-matter, being claimed in a companion application, is disclaimed here: the combination, with a primary apparatus adapted to fold sheets and a secondary apparatus to which such sheets are delivered and by which they are folded, of interchangeable gearing whereby the secondary apparatus is driven at the same or a lesser speed than the primary; also, a primary apparatus adapted to associate sheets, a secondary apparatus adapted to fold such sheets, means for rendering the associating devices 90 inoperative, and means for varying the speed of the secondary apparatus. The following is also disclaimed: the combination, with a rotary carrier capacitated to fold and gather or collect sheets, of a companion carrier provided 95 with fold-receiving nipping-jaws.

100 What is claimed is—

1. The combination, with a primary apparatus consisting of a rotating folding and gathering apparatus, of a secondary apparatus consisting of a pair of rollers, as 65 66, and the interchangeable vibrating folding-blade, and two vibrating sheet-forwarding devices, with change-gearing whereby said secondary apparatus is driven at an equal, a lesser, and a 110 more rapid speed than the primary apparatus, all substantially as described.

115 2. In a sheet-delivery apparatus, the combination, with a primary sheet-manipulating mechanism and means for rotating the same, of a secondary sheet-manipulating apparatus, to which the sheets are delivered from said primary apparatus, and change-gearing connecting the primary and secondary apparatus, whereby the latter is run at a lesser and greater 120 speed than the primary apparatus, while the normal speed of the latter is maintained, all substantially as described.

125 3. In a sheet-delivery apparatus, the combination, with a primary sheet-manipulating mechanism and means for rotating the same, of a secondary sheet-manipulating apparatus, to which the sheets are delivered from said primary apparatus, and change-gearing connect-

ing the primary and secondary apparatus, whereby the latter is run with the same at a lesser and a greater speed than the primary apparatus, while the normal speed of the latter is maintained, all substantially as described.

4. The combination, with a pair of folding-rollers, of means for feeding two sheets over the same so that one edge of each sheet shall overlie said rollers, and means for directing said sheets in succession between said rollers, all substantially as described.

5. The combination, with a pair of folding-rollers, of a slitter for dividing a sheet into two half-sheets, means for feeding said half-sheets so that one edge of each shall overlie said rollers, and means for directing said half-sheets in succession between said rollers, all substantially as described.

6. The combination, with a pair of folding-rollers, of a slitter for dividing a sheet into two half-sheets, means for feeding said half-sheets so that one edge of each shall overlie said rollers, means for directing said half-sheets in succession between said rollers, and means for subsequently folding said sheets, all substantially as described.

7. The combination, with two carriers, as A B, provided with means for associating sheets and for folding sheets, devices for rendering the gathering means inoperative, and devices for causing the folding means to be

inoperative during certain revolutions of its carrier, of a subsequent folding mechanism and means for delivering the sheets thereto, and means for varying the speed of the subsequent folding mechanism, all substantially as described.

8. The combination, with a rotating carrier provided with means for gathering sheets thereon, and with a folding-blade capacitated to move beyond and within the periphery of the carrier, of a cam for thus moving said blade, means for vibrating the cam into and out of operative relation with said folding-blade, and a companion revolving carrier provided with nipping-jaws, all substantially as described.

9. The combination, with the rotating primary sheet-manipulating mechanism, operating to gather or fold, or both, and the secondary sheet-manipulating mechanism, of a shaft, 110, transmitting the motion of the former to the latter, and the wheels 97 and 116, for varying the speed of the latter to double that of the former, while that of the former remains unchanged, all substantially as described.

In testimony whereof I have hereunto set my hand in the presence of two subscribing witnesses.

STEPHEN D. TUCKER.
